UNITED STATES PATENT OFFICE.

JOHN MURL LENTS AND FRANK R. MILLER, OF EVANSVILLE, INDIANA, ASSIGNEES
TO THE OWENS BOTTLE COMPANY, OF TOLEDO, OHIO, A CORPORATION OF OHIO.

APPARATUS FOR FIRE FINISHING GLASS ARTICLES.

Application filed May 27, 1927. Serial No. 194,613.

The present invention relates to improvements in apparatus for fire finishing glass articles and is particularly adapted for use with a continuous conveyor which transfers 5 articles from a forming machine to the receiving end of an annealing leir, as taught for example in our Patent Number 1,626,739, dated May 3, 1927.

Fire finishing of glass articles is sometimes 10 accomplished by holding articles one at a time at a fire finishing station and projecting an acetylene gas flame upon the surfaces to be fire finished. Although this method of fire finishing articles has proven 15 entirely satisfactory as regards the results obtained, the utilization of acetylene gas or the like fuel to provide an intense flame has proven to be costly, and from this viewpoint such a method is objectionable.

20 An object of the present invention is to provide a fire finisher designed to use ordinary city gas as a fuel and thereby minimize the cost of operation.

Another object is to provide a fire finisher 25 by which several articles are simultaneously held at a fire finishing station beneath a series of burners, the holding means operating with the conveyor to effect a step-by-step advance of the articles from one burner to 30 the next succeeding burner whereby each article is individually treated by the several burners before passing beyond the fire finishing station. This construction, whereby the articles are held for a period of time beneath 35 each of the burners, provides means to heat articles to such a degree that fins, cracks, and like surface irregularities are eliminated.

Other objects will be apparent hereinafter.

40 Referring to the accompanying drawings: Fig. 1 is a plan view of the fire finisher.

Fig. 2 is a sectional view taken substantially along the line II—II of Fig. 1.

Fig. 3 is a view taken substantially along 45 the line III—III of Fig. 2.

Fig. 4 is a view taken substantially along the line IV—IV of Fig. 3.

Fig. 5 is a view similar to Fig. 4, showing the article holding jaws separated, and the 50 means for controlling the jaw movement.

Fig. 6 is a detail perspective view of one 55 jaw of the article holder and its carrier.

The bottles or other articles to be fire finished are automatically transferred from 55 a forming machine (not shown) to the re-

ceiving end of an annealing leir (not shown) by an endless conveyor 8 which travels upon a suitable frame 9 supported on uprights 10. During the transfer of the articles from the forming machine to the leir, they are 60 brought by the conveyor to a fire finishing station where they are held in groups for a predetermined period of time while flames are projected upon the upper portions for the purpose of removing irregular surface 65 formations, particularly from the sealing surfaces.

The fire finishing apparatus arranged at the fire finishing station, includes an article holder so formed that it simultaneously 70 holds several articles at said station for treatment. This holder is operated in timed relation to the ejection of articles from the forming machine so that an article is released from the holder and another one is 75 received therein each time an article is ejected from the machine. These articles are held stationary beneath each of the burners of the group before being finally released for transfer to the leir. Thus, the upper portions of the ware are gradually brought to 80 the desired temperature so that a smooth finish is obtained.

Each of the two jaws 11 of the article holder (Fig. 6) comprises a strip of metal 85 or other suitable material so formed that the jaws when brought together provide a series of article receiving pockets 12 in which bottles or other articles are held spaced apart while being fire finished. Vertically spaced bosses 13 are formed on the jaws and are interconnected by webs 14 spaced apart to provide openings 15 into which actuating fingers 23 project (Figs. 5 and 6). Supporting rods 16 extend outwardly from the vertically spaced bosses 13 and have their outer ends interconnected by bars 17 which serve to maintain proper relation between said rods. These rods are supported on grooved rollers 18 mounted on 100 brackets 19 arranged at opposite sides of the conveyor 8. One of these brackets 19 shown at the right of Fig. 2, supports an intermediate grooved roller 20 which is disposed between the two rods 16 to assist 105 the other rollers in providing smooth operation of the holder jaw. The brackets also mount adjustable stops 55 which engage the webs 14 at times to limit movement of the jaws. The rods 16 carrying the jaw at the 110

left of Fig. 2, are guided between a pair of horizontally grooved rollers 18 and a grooved supporting bracket 21 in which the lower rod 16 slides. This bracket 21 is 5 mounted on an arm 22 extending forwardly from the bracket 19 which supports the two horizontally aligned rollers 18.

The article holding jaws 11 are moved toward and away from each other at proper 10 intervals to allow a step-by-step advance of the articles from one pocket to the next succeeding one due to continuous movement of the conveyor 8. The mechanism for actuating the jaws includes a pair of fingers 23 15 fixed to the upper ends of shafts 24 mounted for oscillative movement in bearings 25 on the frame 9 which supports the conveyor 8 (Figs. 2 and 5). The lower ends of these shafts 24 are linked together by a pair of 20 short bars 26 whose inner ends overlap each other, and are formed with slots 27 through which a connecting pin 28 extends. This pin 28 is carried by a block 29 interposed between the slotted ends of said bars and is 25 suitably connected to one end of a coil spring 30 whose other end is secured to an apertured ear 31 formed on one of the brackets or links 10 supporting the conveyor. Thus, 30 it is seen that the coil spring and link arrangement operates to yieldably hold the jaws 11 in the position shown in Fig. 4 so that articles will be momentarily held beneath each burner of the group at the fire finishing station.

35 One of the fingers 23 is formed with an extension 32 at the opposite side of its supporting shaft 24, said extension having pivotal connection to a rod 33 suitably connected to a piston 34 of an air motor 35. This 40 air motor 35 is adapted to be operated in proper timed relation to the ware ejecting operations of the forming machine so that bottles will arrive at the fire finishing station and be discharged therefrom for passage to 45 the leer at proper time intervals, as stated heretofore. The air motor 35 is mounted upon the forwardly extending arm 22 (Figs. 2 and 5) and operates to move the jaws outwardly permitting release of bottles from 50 the holder one at a time, movement of the remaining bottles to the next adjacent pocket, and entry of another bottle into the holder.

The burners 40 are spaced longitudinally 55 of the conveyor 8 at the fire finishing station and depend from a header 41, into one end of which gas or other fuel is injected from a supply pipe 42. This pipe may have direct connection to an ordinary city gas main. The header 41 which supports the group of burners 40 includes an upward extension 43 connected to an arm 44 extending transversely of the conveyor at a point above the bottle holder. This arm 44 is formed 60 with slots 45 through which bolts 46 ex-

tend to provide adjustable connection between said extension 43 and the supporting arm. This arm 44 extends from a plate 47, vertically adjustable on a bar 48 rising from the holder supporting bracket 19, said plate 47 having bolt and slot connection with a pair of bars 49 (Fig. 1) which in turn are slidably connected to the vertical extension 48 (Fig. 2). The unit including the extension 48 and transverse arm 44 is movable 75 up and down relative to the bracket 19 by means of an adjusting screw 50 whose lower end may be swiveled to said unit while its upper end is threaded through a laterally extending ear 51 formed at the upper end 80 of said upward extension 48. Thus, the burners may be adjusted vertically, transversely and longitudinally relative to the conveyor, assuring accurate positioning of the burners over the articles held at the fire 85 finishing station.

The operation of this apparatus may be stated as follows: The bottles or other articles are brought to the fire finishing station on the endless conveyor 8, and as shown in Fig. 90 3, are held at said station in groups by the jaws of the article holder. The pocket formation is such that the articles are uniformly spaced apart and aligned with the downwardly projecting burners 40 so that 95 the flames projected from the burners play upon the sealing surfaces and upper portions of the articles, melting such surfaces sufficiently to eliminate cracks, fins and irregular formations. The jaws 12 of the holder are 100 alternately moved toward and from each other in timed relation to the discharge of articles from the forming machine and are held apart a sufficient period of time to permit the continuously moving conveyor to 105 advance the articles from one pocket of the holder to the next succeeding pocket. At the same time, one article passes beyond the fire finishing station for delivery to the annealing leer, while another article enters 110 the opposite end of the holder for fire finishing (Fig. 3). Periodic actuation of the 115 article holding jaws effects a step by step advance of the articles through the fire finishing station so that each article is individually treated for a predetermined period of time by each burner, thereby insuring sufficient heating of the upper portions of the articles to eliminate fins, cracks and other objectionable surface formations. 120

The burner unit may be adjusted vertically relative to the article holder, permitting use of the apparatus for fire finishing articles of varying heights. The adjustable support for the burner unit permits lateral 125 adjustment of the latter relative to the article holder so that accurate alignment of the burners with the articles being fire finished is readily attainable.

Various modifications may be resorted to 130

within the spirit and scope of our invention.

What we claim is:

1. The combination of a continuously traveling conveyor by which a series of articles are brought in succession to a fire finishing station, a series of longitudinally spaced burners at said station, and means independent of the conveyor to hold articles beneath all of said burners simultaneously.
2. The combination of a horizontally traveling conveyor by which a series of articles are brought in succession to a fire finishing station, a holder adapted to hold a group of articles at said station, means including a series of burners to apply heat to the upper ends of said articles simultaneously, and means to actuate the article holder at predetermined time intervals to release one article at a time from the holder and cause a step-by-step advance of the remaining articles in the holder.
3. The combination of a continuously traveling conveyor by which a series of articles are brought in succession to a fire finishing station, a series of longitudinally spaced burners at said station, means independent of the conveyor to simultaneously hold articles beneath all of said burners, and means actuating the holding means permitting the conveyor to effect a step-by-step advance of articles in the holding means for individual treatment by each of said burners.
4. The combination of a horizontally traveling conveyor by which a series of articles are brought in succession to a fire finishing station, a fire finisher arranged at said station including a series of longitudinally spaced depending burners, means to hold the articles at said station, and means operated in timed relation to the conveyor movements to actuate said article holder whereby the articles are advanced by the conveyor from one point to another in the holder for individual treatment by each of the burners.
5. In a fire finishing apparatus, the combination of a continuously traveling conveyor or by which a series of articles are brought in succession to a fire finishing position, a pair of gripping jaws constructed to provide a series of individual article holding pockets, burners individual to the pockets, and means to actuate the jaws permitting release of one article at a time from the jaws and a step-by-step advance of the remaining articles to the next succeeding pockets in said holder.
6. The combination of a horizontally traveling conveyor by which a series of articles are brought in succession to a fire finishing station, an article holder arranged in proximity to the upper side of the conveyor and comprising a pair of jaws formed with individual article holding pockets, means to actuate said jaws whereby the articles are permitted to advance with the conveyor from one pocket to the next adjacent pocket, and fire finishing means to operate on the articles when in said pockets.
7. The combination of a horizontally traveling conveyor by which a series of articles are brought in succession to a fire finishing station, an article holder arranged in proximity to the upper side of the conveyor at said station and comprising a pair of jaws formed with individual article holding pockets, means to actuate said jaws whereby the articles are permitted to advance with the conveyor from one pocket to the next succeeding pocket, burners individual to the pockets to project flames against articles held in said pockets, and means adjustably supporting said burners permitting lateral and vertical adjustment relative to the pockets.
8. The combination of a continuously traveling conveyor by which a series of articles are brought in succession to a predetermined station, an article holder at said station comprising a pair of coacting jaws formed with individual pockets to simultaneously hold a group of articles spaced apart, and an automatic means to alternately open and close the pockets in timed relation to movement of the conveyor permitting advance of articles from one pocket to the next succeeding pocket.
9. In combination, a continuously traveling conveyor by which a series of articles are brought in succession to a predetermined station, means to arrest movement of articles at said station including a pair of coacting jaws constructed to form individual article holding pockets, guide rods extending outwardly from said jaws, rollers guiding and supporting said rods, and means actuating the jaws in timed relation to the movement of said conveyor, causing the articles to be momentarily held in each pocket before being finally released from said jaws.
10. In combination, a continuously traveling conveyor by which a series of articles are brought in succession to a predetermined station, means to arrest movement of articles at said station including a pair of coacting jaws constructed to form individual article holding pockets, guide rods extending outwardly from said jaws, rollers guiding and supporting said rods, means actuating the jaws in timed relation to movement of said conveyor, causing the articles to be momentarily held in each pocket before being finally released from said jaws, and means to project flames upon the upper ends of articles while held in said pockets.
11. The combination of a continuously traveling conveyor by which articles are brought in succession to a fire finishing station, a fire finisher at said station including a series of downwardly projecting burners, article holding means positioned at all times at said

station operating with said conveyor to cause a step-by-step advance of the articles beneath said burners whereby articles are momentarily held in position for individual heat treatment by each of the burners, and laterally and vertically adjustable supporting means for said burners.

12. In fire finishing apparatus, the combination of a series of burners, and means including a continuously traveling conveyor for bringing a series of articles in succession into fire finishing position and causing each article to be brought into operative relation to the several burners in succession, said means being timed and arranged to supply articles concomitantly to all the burners.
13. In fire finishing apparatus, the combi-

nation of a series of burners, means including a continuously traveling conveyor for advancing a series of articles step-by-step into operative relation to the burners and causing each article to be brought into positions to be acted upon by each of the burners in succession, and means to maintain said articles in such relation that as each article is moved beyond a burner, the next succeeding article is brought into operative relation to said burner.

Signed at Evansville, in the county of Vanderburg and State of Indiana, this 23rd day of May, 1927.

JOHN MURL LENTS.
FRANK R. MILLER.
